UNITED STATES PATENT OFFICE.

HARRY J. PURPLE, OF NEWTON, MASSACHUSETTS, ASSIGNOR TO UNITED DRUG COMPANY, OF BOSTON, MASSACHUSETTS, A CORPORATION OF MASSACHUSETTS.

SHAVING-STICK HOLDER.

1,338,156.

Specification of Letters Patent. Patented Apr. 27, 1920.

Application filed March 31, 1919. Serial No. 286,358.

To all whom it may concern:

Be it known that I, HARRY J. PURPLE, a citizen of the United States, and resident of Newton, county of Middlesex, State of Massachusetts, have invented an Improvement in Shaving-Stick Holders, of which the following description, in connection with the accompanying drawings, is a specification, like characters on the drawings representing like parts.

This invention relates to the holders used with shaving sticks and like articles. While I have specifically mentioned a shaving stick, the invention is applicable to other articles which are handled or used in a similar way, that is to say, by a rubbing action which results in a gradual wearing away of the material applied. The shaving stick, however, is perhaps the most generally known article of this class and as I anticipate a major field of usefulness for my device in its application to shaving sticks, I shall in the following specification and claims refer more particularly to a shaving stick, using that word in an exemplary sense embracing other articles of the same general type in construction and use.

My invention will best be understood by reference to the following description taken in connection with the accompanying drawings wherein:

Figure 1 is a side view of the complete container;

Fig. 2 is a central vertical section thereof showing the stick in elevation;

Fig. 3 is a view of the stick as it appears after the cover or cap of the container is lifted and shows the stick and its hand grip in position for use; and

Fig. 4 is an enlarged section on the line 4—4 of Fig. 3 and with parts shown in another position in dotted lines.

Referring to the drawings, I there show a construction of that type wherein the shaving stick is mounted in a grip which also serves as a base for the container and with which cooperates a cover inclosing the major portion of the stick when it is not in use. My improvements more particularly apply to the construction of the grip which forms the base of the container.

This grip, which is secured to the base portion of the stick of soap 5, is preferably formed as indicated in Fig. 2 from a metal

stamping providing a base plate 7 conveniently formed with a marginal rim or bead 9. From one side of the base portion 9 rises a flange 11 (see Fig. 4), providing an abutment against which the base of the stick is placed and adapted to fit the same. When the stick is round, as is usually the case, this flange may conveniently take the form of a semicircle. Herein the flange is extended integrally, as shown in dotted lines in Fig. 4, to provide a bendable band 13 of sufficient length to complete the circuit of the base of the stick when bent and this band may be provided with a terminal tongue 15 adapted to fit a slot 17 in the corresponding end of the flange 11.

It will be understood that the part is supplied to the assembler with the movable extension 13 in dotted line position. The operative inserts the shaving stick laterally, pressing it against the abutment flange 11, and then swings over the band 13, fitting it around the base of the stick and causing the latter to press against the abutment, and finally secures the movable section in position (in the present example) by inserting the tongue 15 through the slot 17 and locking it therein by embedding it in the soap, the parts 11 and 13 in co-operation forming a closed ring gripping the end of the stick. This ring will ordinarily, when the stick is cylindrical as is customary, form a ring in the more restricted sense of the word, but it may form a ring in the broader sense, that is, any closed open-centered figure that the conformation of the stick may require. Preferably this ring has provision for securing the stick against longitudinal withdrawal from the grip and herein I show spurs 19 struck up from the metal, which spurs are embedded in the stick.

To provide a complete package, a cap or cover 21 is provided adapted to inclose the stick 5 and having an open end which may fit over the ring provided by the parts 11 and 13 and seat on the beading 9 as shown in Figs. 1 and 2.

The grip described forms a convenient handle for holding the stick in use. After the stick has been used, a new one may readily be inserted by releasing and swinging back the movable portion 13, withdrawing the small butt of stick remaining, and inserting a new stick in its place. The

grip holds the stick firmly and is not loosened by any shrinkage due to drying of the soap that may take place after it has been placed in position. The engagement 5 with the soap is furthermore of such a nature as will not readily be loosened by the breaking away of portions of the soap. The assembly in the first instance and in refilling is simple and requires no special 10 treatment of the soap stick itself or special materials or tools to form the connection.

Having thus described an illustrative embodiment of my invention, what I claim as new and desire to secure by Letters Patent 15 is:—

1. A shaving stick having a grip attached to one end thereof and comprising a base having an upstanding flange portion extending partly around the same and receiving 20 one side of the stick, said portion being prolonged as a bendable strip which when bent forms in coöperation with said flange portion a ring gripping the end of the stick.
- 25 2. A shaving stick having a grip attached to one end thereof and comprising a base having an upstanding flange portion extending partly around the same and receiving one side of the stick, said portion being 30 prolonged as a bendable strip which when bent forms in coöperation with said flange portion a ring gripping the end of the stick, said flange portion having a slot and said strip having a tongue entering said slot and 35 embedded in the stick.
3. A shaving stick having a grip attached to one end thereof and comprising a base having an upstanding flange portion extending partly around the same and receiving 40 one side of the stick, said portion being prolonged as a bendable strip which when bent forms in coöperation with said flange portion a ring gripping the end of the stick, said parts having inward projections 45 adapted laterally to enter the body of the stick and hold the same against longitudinal withdrawal when the ring is con-

stricted about the base of the stick by the bending of said portion.

4. A shaving stick having a grip attached 50 to one end thereof and comprising a base having an abutment rising from one side to receive one side of the stick and an opposed movable portion having an open position permitting the introduction of the stick laterally across said base and against said abutment and a closed position bearing 55 against the stick and holding it against said abutment.

5. A shaving stick having a grip attached 60 to one end thereof and comprising a base having an abutment rising from one side to receive one side of the stick, an opposed movable portion having an open position permitting the introduction of the stick 65 laterally across said base and against said abutment and a closed position bearing against the stick and holding it against said abutment, and a releasable locking means to hold said movable portion in position. 70

6. A shaving stick having a grip attached to one end thereof and comprising a base having an abutment rising from one side to receive one side of the stick and an opposed movable portion having an open position 75 permitting the introduction of the stick laterally across said base and against said abutment and a closed position bearing against the stick and holding it against said abutment, said parts having inwardly directed projections entering the body of the 80 stick.

7. A shaving stick having a grip attached to one end thereof and comprising a base having a flange portion to receive one side 85 of the base of the stick, a member swingably mounted and forming in coöperation with said flange portion a ring inclosing the base of the stick and means for locking said portion in position. 90

In testimony whereof, I have signed my name to this specification.

HARRY J. PURPLE.
